COUPLER

Edmund P. Kinne, Alliance, Ohio, assignor to
American Steel Foundries, Chicago, Ill., a cor-
poration of New Jersey

Application February 24, 1931, Serial No. 517,676

13 Claims. (Cl. 213—127)

This invention pertains to couplers, and more particularly to a coupler construction wherein creeping is prevented.

In some types of couplers a great deal of trouble has been experienced due to improper operation of the anti-creep. Two principal things have happened to it. In the earlier couplers the anti-creep did not function. Various changes were made and then difficulty developed on account of the coupler not unlocking properly. That is, the parts were not properly designed to give positive action.

It is therefore an object of this invention to provide a lock anti-creeping means which is simple and effective, fulfills all requirements of manufacture and service, yet at the same time will not interfere with the operation of the various parts of the coupler.

Another object is to provide a coupler construction wherein a positive action is secured, yet at the same time the anti-creep will function under all operating conditions yet is readily released by proper operation of the coupler operating mechanism.

A further object is to provide a coupler construction wherein the operating mechanism provides means for securing positive action in uncoupling.

With these and various other objects in view, the invention may consist of certain novel features of construction and operation, as will be more fully described and particularly pointed out in the specification, drawings and claims appended hereto.

In the drawings, which illustrate an embodiment of the device and wherein like reference characters are used to designate like parts—

Figure 1 is a fragmentary sectional elevation through my improved coupler showing the lock in locked position, the dotted lines indicating the position of the lifter when the coupler is being operated to unlocking position;

Figure 2 is a fragmentary sectional elevation corresponding to Figure 1 showing the parts in anti-creep position;

Figure 3 is a fragmentary sectional elevation corresponding to Figure 1 showing the conditions causing interference in type D bottom lift couplers resulting in failure of the coupler to unlock when this type of coupler was provided with a lifter link having an extended shoulder.

Figure 4 is a fragmentary sectional elevation of the type D bottom lift coupler showing the lock in such a position that the lifter link engages the anti-creep lug;

Figure 5 is a fragmentary sectional view taken in the planes represented by line 5—5 through the coupler shown in Figure 4 showing my improved lock leg aperture rear wall;

Figure 6 is a side elevation of the lifter adapted for the use of the coupler shown in Figure 4;

Figure 7 is a fragmentary sectional elevation corresponding to Figure 1 showing the minimum anti-creep with the lock leg to the rear;

Figure 8 is a view similar to Figure 7 showing unlocking with the lock leg forward;

Figure 9 is a fragmentary sectional elevation similar to Figure 1 of the drawings showing the lock in its abnormally low position for connecting the lifter thereto; and

Figure 10 is a fragmentary sectional elevation corresponding to Figures 1 and 9 of the drawings disclosing more in particular the lock in its unlocked position and the structure necessitating clearance for the lock leg above the anti-creep leg and front wall of the coupler head.

Referring first of all more particularly to Figures 4 to 6 inclusive, a form of coupler is shown wherein the lifter link 19 is pivotally secured to the lock leg 12 and provided with an outwardly extending shoulder 14 substantially in alignment with the pivot pin 16 whereby a shoulder is provided which is adapted to have cooperative operation with the shoulder or anti-creep lug 18 provided in the lock leg chamber 20 of the coupler 22. With this type of coupler there was originally a fore and aft dimension as indicated at 22, this dimension being such that the anti-creep was entirely ineffective. That is, when vertical movement was caused in service by operation of the train, the lock could rise sufficiently so that the anti-creep means would be released. In order to render the anti-creep effective, the rear wall was provided with lug 24 which limited the tilting movement of the lock leg whereby the anti-creep was rendered effective, and, at the same time, effective operation of the release was sought. This feature is the subject matter of my Patent No. 1,520,251, issued December 23, 1924. I have further improved this construction by providing the rear wall with an additional lug 25 with a corresponding cooperating portion 27 provided on the lock, the surface 29 of the lock cooperating with the lug 24 so that in reality the lugs 24 and 25 form a pair of spaced guiding lugs which prevent side tipping of the lock which would not be prevented with only a single lug, for after a time wear would increase the clearances which must be maintained between the lock leg and the wall of the lock chamber for permitting proper opera-

tion. It will therefore be apparent that in the absence of lug 25 the lock leg would be free to move in a clockwise direction as viewed in Figure 5 of the drawings, especially after wear has occurred between the parts so that the overhanging relation between the lift link and anti-creep lug is increased thereby tending to render unlocking ineffective.

In this construction, as well as in the extended shoulder construction shown in Figure 3, there was still a considerable expanse of lock leg chamber shown at 26, and difficulty was encountered in that if the lifter link 16 twisted slightly it caused a binding at the upper edge 28 of the slot 30, the lock pivoting around the point of support 32 causing the lower portion of the lock leg to move a substantial distance toward the front wall 36 of the coupler, which disposed the extended shoulder 38 or the shoulder 14 in a position with respect to the shoulder or anti-creep lug 18 wherein it was impossible to release the anti-creep to operate the coupler. During upward movement of the lifter link, friction on the surface 28 between the pin 16 and leg 12 tends to cause the lock leg to tilt forward about its pivot point 32. When the pivot pin 16 finally slides up the slot after throwing the lock leg against the front wall, the projection on the shoulder interferes with the anti-creep lug before the pin 16, which constitutes the loose connection in the slot 30, reaches the rear of the slot to thrust the lock against the back of the lock chamber.

Referring now more particularly to Figures 1 and 2, the lifter link 39 as shown in Figure 3 with the extended shoulder 38, is retained but there is provided a thickened wall portion 40 on the front wall adjacent the lug 18 so that the effective width 42 of the lock leg chamber is reduced. In this construction, the forward pivotal action of the lock leg is reduced to such a degree that even though the lock leg is in contact with the front wall 40, the extended shoulder 38 in its upward movement in the slot 30 permits release of the anti-creep such as indicated in the dotted lines in Figure 1. That is, the shoulder 38 will clear the anti-creep lug 18. Direct vertical movement of the lock leg, however, still necessarily causes engagement of the shoulder 38 and 18 whereby the anti-creep is effective as shown in Figure 2. It will thus be seen that with the construction illustrated in Figures 1 and 2, there is provided a coupler construction which is positive in operation, and, though tipping of the parts may occur due to wear, the relation of the parts is always such that the anti-creep will function in direct vertical movement of the lock and lifter, but will be rendered inoperative by proper operation of the uncoupling rod for releasing the knuckle or raising the lock.

As clearly disclosed in the drawings, the lug 40 defines the front wall of the coupler head which cooperates with the lock leg whereby the lift link and anti-creep lug effect a positive anti-creep and positive unlocking. As shown in Figures 9 and 10, the front wall as defined by this lug 40 is offset forwardly and the rear wall of the coupler is formed for effecting well-defined results as will be set out more fully.

In assembling the lock and lift link, the lock leg 12 is lowered as shown in Figure 9 of the drawings to a position so that the lower end of slot 30 will be disposed below the head of the coupler to receive pivot pin 16 of the lift member. This lowering of the lock leg is permitted by the for-

ward inclined offset 17 of the front wall of the coupler as defined by the lug 40 and also by the formation of the rear wall of the coupler head which slopes rearwardly as at 19 to provide clearance with the lock leg. It will also be noted that the rear wall at 19 is also adapted to cooperate with the lock leg as at 23 just above the lock-set shoulder 25^a for guiding the lock leg into the position shown in Figure 9 whereby this assembly of the parts can be effected.

The upper portion of the front wall as defined by the lug 40 is likewise offset forwardly to provide for the various movements of the lock leg. In a coupler of the type described, the knuckle thrower, as shown in Figure 10, has limited movement about its pivot whereby the end 27^a cooperating with the lock leg has limited movement. During movement of the lock into its lock-set position, the lock leg engages the end 27^a and when the shoulder 25^a thereof finally seats upon the same, this end of the knuckle thrower assumes the full line position of Figure 10. When the knuckle of the coupler is opened, the tail 29^a of the knuckle raises the lock, tilts it and drags the lock leg from its seat on the top of the thrower. The friction between the shoulder 25^a and end 27^a is sufficient during this opening of the tail and the movement of the lock into its unlocked position from lock-set position to create a tendency to move the end of the thrower into its dotted line position of Figure 10, and it is because of this movement of the thrower that it is necessary to offset the front wall as defined by lug 40 as at 31.

It will also be appreciated that the formation of the rear wall at 19 permits proper movement of the lock leg between lock-set and locked positions, as well as between lock-set and unlocked positions.

Referring to Figure 7, there are certain times when the lock leg 12 assumes a position contacting the rear wall. That is, it is disposed to the rear so that the condition of operation is that the slot 30 must be of such length as to provide a proper horizontal movement for the anti-creep 45 engaging member 38. More specifically, the distance C defining the centers of the pivot pin 16 must be equal to or greater than the distance B.

Referring now to Figure 8, the lock leg here is forward, and, in order to obtain positive unlocking, the distance C must be equal to or greater than distance D.

It is to be understood that I do not wish to be limited by the exact embodiment of the device shown, which is merely by way of illustration and not limitation, as various and other forms of the device will of course be apparent to those skilled in the art without departing from the spirit of the invention or the scope of the claims.

I claim:

1. In a coupler, the combination of a head having an opening for passage of the leg of a lock, a lock having a leg movable in said opening, a bottom lift member for lifting said lock from a locking position, said member having a shoulder, and an anti-creep lug extending into said opening and cooperating with said shoulder to prevent said lock from creeping into a non-locking position, the front and rear walls of said opening cooperating with forward and rear surfaces on said lock leg to provide limited forward or rearward movement of said lock leg about a pivot point above the engagement of the lock leg surfaces therewith and to permit substantially vertical movement of the lock in service, said front wall

being provided with a forwardly offset surface adapted to allow a greater freedom of movement of the lock leg between said front and rear walls of the opening when the lock leg is in an abnormally lower position and the lock is being assembled with said head and the lock lifter member is being assembled with said lock.

2. In a coupler, the combination of a head having an opening for passage of the leg of a lock, a lock having a leg movable in said opening, a bottom lift member for lifting said lock from a locking position, said member having a shoulder, and an anti-creep lug extending into said opening and cooperating with said shoulder to prevent said lock from creeping into a non-locking position, the front and rear walls of said opening cooperating with forward and rear surfaces on said lock leg to provide limited forward or rearward movement of said lock leg about a pivot point above the engagement of the lock leg surfaces therewith and to permit substantially vertical movement of the lock in service, said front wall being provided with a forwardly offset surface adapted to allow a greater freedom of movement of the lock leg between said front and rear walls of the opening when the lock leg is in an abnormally lower position and the lock is being assembled with said head and the lock lifter member is being assembled with said lock, said front wall being further provided with a forwardly offset surface adapted to allow movement of said lock leg during forward movement thereof upon unseating of the same from its lock-set position.

3. In a coupler, the combination of a head having an opening for passage of the leg of a lock, a lock having a leg movable in said opening, a bottom lift member for lifting said lock from a locking position, said member having a shoulder, and an anti-creep lug extending into said opening and cooperating with said shoulder to prevent said lock from creeping into a non-locking position, the front and rear walls of said opening cooperating with forward and rear surfaces on said lock leg to provide limited forward or rearward movement of said lock leg about a pivot point above the engagement of the lock leg surfaces therewith and to permit substantially vertical movement of the lock in service, said lift member being movable relative to said leg whereby said shoulder clears said lug during locking and unlocking movement thereof, said front and rear walls being disposed to maintain said lock leg in a locking position whereby said anti-creep lug overhangs said shoulder to cooperate therewith for effecting an anti-creep, said rear wall and said lock leg being adapted to bear upon each other on both sides of a line substantially through the center of said leg and opening substantially parallel with the longitudinal axis of said coupler thereby tending to prevent twisting of said lock which would tend to increase the overlapping relation of said lift member and anti-creep lug thus tending to render unlocking ineffective.

4. In a coupler, the combination of a head having an opening for passage of the leg of a lock, a lock having a leg movable in said opening, a bottom lift member for lifting said lock from a locking position, said member having a shoulder, and an anti-creep lug extending into said opening and cooperating with said shoulder to prevent said lock from creeping into a non-locking position, the front and rear walls of said opening cooperating with forward and rear surfaces on said lock leg to provide limited forward or rearward movement of said lock leg about a pivot point

above the engagement of the lock leg surfaces therewith and to permit substantially vertical movement of the lock in service, the upper portion of said front wall being offset forwardly to permit free movement of the leg during forward movement thereof upon unseating of the same from its lock-set position and the lower portion of said front wall being offset forwardly to permit said lock leg to be lowered below operative position for the assembly of said lift member with said lock leg.

5. In a coupler, the combination of a head having an opening for passage of the leg of a lock, a lock having a leg movable in said opening, a bottom lift member for lifting said lock from a locking position, said member having a shoulder, and an anti-creep lug extending into said opening and cooperating with said shoulder to prevent said lock from creeping into a non-locking position, the front and rear walls of said opening cooperating with forward and rear surfaces on said lock leg to provide limited forward or rearward movement of said lock leg about a pivot point above the engagement of the lock leg surfaces therewith and to permit substantially vertical movement of the lock in service, said front wall being provided with a forwardly offset surface adapted to allow a greater freedom of movement of the lock leg between said front and rear walls of the opening when the lock leg is in an abnormally lower position and the lock is being assembled with said head and the lock lifter member is being assembled with said lock, said rear wall having a rearwardly extending portion above a foremost substantially vertical surface thereof which cooperates with said leg when said lock is in a normal unlocked position for guiding said leg into said abnormally low position for assembling said lock lift member and lock.

6. In a coupler, the combination of a head having an opening for passage of the leg of a lock, a lock having a leg movable in said opening, a bottom lift member for lifting said lock from a locking position, said member having a shoulder, and an anti-creep lug extending into said opening and cooperating with said shoulder to prevent said lock from creeping into a non-locking position, the front and rear walls of said opening cooperating with forward and rear surfaces on said lock leg to provide limited forward or rearward movement of said lock leg about a pivot point above the engagement of the lock leg surfaces therewith and to permit substantially vertical movement of the lock in service, said front wall being provided with a forwardly tapering offset surface adapted to allow a greater freedom of movement of the lock leg between said front and rear walls of the opening when the lock leg is in an abnormally lower position and the lock is being assembled with said head and the lock lifter member is being assembled with said lock, said rear wall having a rearwardly extending inclined portion above a foremost substantially vertical surface thereof which cooperates with said leg when said lock is in a normal unlocked position for guiding said leg into said abnormally low position for assembling said lock lifter member and lock.

7. In a coupler, the combination of a head having an opening for passage of the leg of a lock, a lock having a leg movable in said opening, a bottom lift member for lifting said lock from a locking position, said member having a shoulder extending in the direction of the length of said coupler, and an anti-creep lug extending into

said opening and cooperating with said shoulder to prevent said lock from creeping into a non-locking position, the front and rear walls of said opening cooperating with forward and rear surfaces on said lock leg to provide limited forward or rearward movement of said lock leg about a pivot above the engagement of the lock leg surfaces therewith and to permit substantially vertical movement of the lock in service, said lift member being movable relative to said leg whereby said shoulder clears said lug during locking and unlocking movements thereof, said front and rear walls being constructed and arranged to maintain said lock leg in a locking position whereby the greater portion of said anti-creep lug extending beyond the lock cooperating portion of one of said walls overhangs said shoulder to cooperate therewith for effecting a positive anti-creep and whereby a positive unlocking is effected by the positive disengagement of the anti-creep lug and shoulder at all times as the lock leg is raised.

8. In a coupler, the combination of a head having an opening for the passage of the leg of a lock, a knuckle pivotally connected to said head,

25 a lock for said knuckle having a leg movable in said opening, a bottom lift member for lifting said lock from a locking position, an anti-creep lug extending into said opening adapted to be engaged by said lift member for preventing said lock from creeping into a non-locking position, and laterally spaced lugs cooperating with said lock and extending into said opening tending to prevent twisting of said lock which would tend to increase the overlapping relation of said lift member and anti-creep lug thus tending to render unlocking ineffective.

9. In a coupler, the combination of a head having an opening for the passage of the leg of a lock, a knuckle pivotally connected to said head, 40 a lock for said knuckle having the leg movable in said opening, a bottom lift member for lifting said lock from a locking position, said member having an extended shoulder portion offset therefrom in the direction of the length of the coupler, 45 anti-creep means adapted to be engaged by the extended shoulder portion for preventing said lock from creeping into a non-locking position, and laterally spaced lugs cooperating with said lock and extending into said opening tending to prevent twisting of said lock which would tend to increase the overlapping relation of said lift member and anti-creep lug thus tending to render unlocking ineffective.

10. In a coupler, the combination of a head 55 having an opening for the passage of the leg of a lock, a knuckle pivotally connected to said head, a lock for said knuckle having a leg movable in said opening, a bottom lift member for lifting said lock from a locking position, an anti-creep lug 60 extending into said opening adapted to be engaged by said lift member for preventing said lock from creeping into a non-locking position when said leg is in a given position, the rear wall of said opening and said lock leg being adapted to bear 65 upon each other on both sides of a line substantially through the center of said leg and opening substantially parallel with the longitudinal axis of said coupler thereby tending to prevent twisting of said lock which would tend to increase the 70 overlapping relation of said lift member and anti-creep lug thus tending to render unlocking ineffective.

11. In a coupler, the combination of a head 75 having an opening for passage of the leg of a lock,

a lock having a leg movable in said opening, a bottom lift member for lifting said lock from a locking position, said member having a shoulder, and an anti-creep lug extending into said opening and cooperating with said shoulder to prevent said lock from creeping into a non-locking position, the front and rear walls of said opening cooperating with forward and rear surfaces on said lock leg to provide limited forward or rearward movement of said lock leg about a pivot point above the engagement of the lock leg surface therewith and to permit substantially vertical movement of the lock in service, said front and rear walls being disposed to maintain said lock leg in a locking position whereby a positive anti-creep is effected between said shoulder and anti-creep lug and a positive unlocking is effected by the positive disengagement of the anti-creep lug and shoulder at all times as the lock leg is raised, said front wall being provided with a forwardly offset surface adapted to allow normal operative movement of said lock leg during forward movement thereof upon unseating of the same from its lock-set position.

12. In a coupler, the combination of a head 25 having an opening for passage of the leg of a lock, a lock having a leg movable in said opening, a bottom lift member for lifting said lock from a locking position, said member having a shoulder, and an anti-creep lug extending into said opening and cooperating with said shoulder to prevent said lock from creeping into a non-locking position, the front and rear walls of said opening cooperating with forward and rear surfaces on said lock leg to provide limited forward or rearward movement of said lock leg about a pivot point above the engagement of the lock leg surface therewith and to permit substantially vertical movement of the lock in service, said front and rear walls being disposed to maintain 30 said lock leg in a locking position whereby a positive anti-creep is effected between said shoulder and anti-creep lug and a positive unlocking is effected by the positive disengagement of the anti-creep lug and shoulder at all times as the lock leg is raised, said front wall being provided with a forwardly offset surface adapted to allow a greater freedom of movement of the lock leg between said front and rear walls of the opening when the lock leg is in an abnormally lower 35 position and the lock is being assembled with said head and the lock lift member is being assembled with said lock.

13. In a coupler, the combination of a head 55 having an opening for passage of the leg of a lock, a lock having a leg movable in said opening, a bottom lift member for lifting said lock from a locking position, said member having a shoulder, and an anti-creep lug extending into said opening and cooperating with said shoulder to prevent said lock from creeping into a non-locking position, the front and rear walls of said opening cooperating with forward and rear surfaces on said lock leg to provide limited forward or rearward movement of said lock leg about a pivot point above the engagement of the lock leg surface therewith and to permit substantially vertical movement of the lock in service, said front and rear walls being disposed to maintain 60 said lock leg in a locking position whereby a positive anti-creep is effected between said shoulder and anti-creep lug and a positively unlocking is effected by the positive disengagement of the anti-creep lug and shoulder at all times as the 65

70 anti-creep lug and shoulder at all times as the 75

lock leg is raised, said front wall being provided with a forwardly offset surface adapted to allow a greater freedom of movement of the lock leg between said front and rear walls of the opening when the lock leg is in an abnormally lower position and the lock is being assembled with said head and the lock lift member is being assembled

with said lock, said front wall being further provided with a forwardly offset surface adapted to allow normal operative movement of said lock leg during forward movement thereof upon unseating of the same from its lock-set position. 5

EDMUND P. KINNE.

CERTIFICATE OF CORRECTION.

Patent No. 2,001,197.

May 14, 1935.

EDMUND P. KINNE.

It is hereby certified that error appears in the printed specification of the above numbered patent requiring correction as follows: Page 3, second column, line 39, claim 5, for "lifted" read lifter; and page 4, second column, line 73, claim 13, for "positively" read positive; and that the said Letters Patent should be read with these corrections therein that the same may conform to the record of the case in the Patent Office.

Signed and sealed this 25th day of June, A. D. 1935.

Bryan M. Battey
Acting Commissioner of Patents.
